COKING RETORT OVEN

Joseph Becker, Pittsburgh, Pa., assignor, by
mesne assignments, to Koppers Company, a
corporation of Delaware

Application July 9, 1935, Serial No. 30,533

9 Claims. (Cl. 202—151)

My invention relates to improvements in coking retort ovens, and more particularly horizontal coke ovens of the cross-regenerative and under-jet underfired type; and preferably it is embodied in ovens of said type that are the Becker crossover ovens of my Patents 1,374,546 and, among others, 1,904,191 and having the under-jet type of construction exemplified in my further Patents 1,704,239 and 2,003,574 and in certain figures of my co-pending application Serial No. 2,564, filed January 19, 1935; and the invention is further applicable to other cross-regenerative under-jet horizontal coke ovens.

My invention has for an object the provision of means for utilizing the stack draft through the cross-regenerative and flue systems of such oven batteries to provide a uniformly distributed and positively effective ventilation of the sub-structure passages in which operators manipulate the under-jet regulation devices beneath such batteries, and at the same time to employ the ventilation draft from such passages to supply the air requirement for combustion in the ovens and to distribute the influx of such air in a manner that uniformly and constantly moderates the high temperature to which the refractory pad or mat directly supporting the cross-regenerators would otherwise be brought by the intense radiation from the bases of such regenerators; and the invention has for further objects such other operative or structural advantages or results as may be found to obtain in the structures and operation hereinafter described or claimed.

In the accompanying drawings, forming a part of this specification and showing for purposes of exemplification certain preferred forms and manner in which the invention may be embodied and practiced, but without limiting the claimed invention specifically to such illustrative instance or instances;

Figure 1 shows a longitudinal cross-section in elevation through one of the ovens comprising a battery of the aforesaid cross-regenerative under-jet Becker ovens including an embodiment of my invention;

Fig. 2 is a section on the line II—II of Fig. 1 and shows the underfiring arrangement of a plurality of ovens forming one end of an oven battery, wherein the rich-gas introduction into the heating flues for underfiring purposes is effected using the under-jet principle, and the waste gases are flowed to the flues in the opposite heating-wall in the well known cross-over manner exemplified by the above-mentioned Becker cross-

over patents, the said waste gases passing on through the waste-heat regenerators and thence to the stack disposal;

Fig. 3 shows an elevational view, parts in section, of a type of flow-box construction showing the disposition of the valves and their actuating means which may be used to control the air and waste-heat flow in this exemplification of my invention;

Fig. 4 shows a plan view of the same flow-box construction.

Fig. 5 is a horizontal sectional view through the battery on the line V—V of Fig. 1, to show in plan the arrangement of the subsole-channels that my invention provides beneath the cross-regenerator sole-channels and just above the pad that directly supports the regenerators of the battery, to provide for the intake of air from the battery sub-structure and for the distribution and delivery of such air to the regenerator sole-channels;

Fig. 6 is a horizontal sectional view taken through the battery along lines VI—VI of Fig. 1 to show the arrangement of the supporting piers and work-passages in the sub-structure of the battery and also the disposition of the rich-gas main and of the lateral waste-gas tunnel structures on the coke-side and pusher-side respectively of the sub-structure of the battery.

Like reference numerals indicate like parts in all of the above figures of the drawings.

The coking retort oven or oven battery comprises a series of horizontal coking-chambers 10 and intermediate heating-walls 12 therefor and side-by-side therewith, and series of side-by-side regenerators 13, 14 below and paralleling the series of coking-chambers and heating-walls. The heating-walls comprise vertical heating-flues 15 disposed in sets in each heating-wall, the sets or pairs of mutually adjacent heating-walls being 40 mutually connected by crossover-conduits 16 through which the hot combustion products or waste-heat gases from the up-flow or burning set of heating-flues in one heating-wall flow over to the down-flow set of heating-flues in the other 45 heating-wall of the pair, the up-flow being reversed and the up-flow set becoming the down-flow set and vice versa upon the reversal of the regenerative system. The aforesaid cross-regenerators, below and paralleling the series of coking-chambers and heating walls, are directly supported on a pad or mat 11 and are disposed in groups of four, each group having two middle regenerators 13, 13 that may be employed for preheating poor or weak gas and are flanked by 50 55

air regenerators 14, 14, or all four regenerators in the group 13, 13, 14, 14 may be employed for preheating air when the oven is underfired with rich gas from its under-jet connections. At any given time, alternate groups of regenerators operate for up-flow of air, or of preheated gas and air, and the intermediate groups for down-flow of waste gases, these relations being reversed in each period of reversal of the regenerative system. The regenerators 13, 13 at their tops connect through ducts 17, 17 with heating-flues in heating-walls that are on respectively opposite sides of the coking-chambers directly above such pair of regenerators 13, 13; and the two regenerators 14, 14 which flank said regenerators 13, 13 in each group, each communicate respectively, through ducts 18, with the heating-flues in one of the said two heating-walls that are both in connection with said regenerators 13, 13. Such two heating-walls operate simultaneously in the same direction in respect of each other and respectively belong to two adjacent pairs of the pairs of heating-walls that are connected by cross-over conduits 16 in the manner before described. The pillar-walls 23, supporting the battery sub-structure, that are between each pair of regenerators 13, 14 that simultaneously operate in the same direction, are provided with gas ducts that lead from the heating-flue at the top of such pillar-wall down through the pillar-wall and the underlying pad to the under-jet connections beneath the pad that communicate with the rich-gas supply conduits and main in the passages of the sub-structure of the battery.

When underfiring with rich gas, that is with gas which is produced as a result of the distillation or coking process, the same is introduced into the battery structure from the gas main 20 in the battery basement. This main parallels the lengthwise axis of the battery its entire length. At intervals along this gas main and rising perpendicularly therefrom, are found the branch lines 21 which are communicably connected with the distributing lines 22 situated beneath each series of vertically disposed heating flues in an oven wall and extending substantially parallel thereto the entire length of each flue series. Each heating flue 15 (Fig. 2) is supplied at its lower end with rich gas by means of the vertically rising ducts 19 which extend from the branch lines 22 through the oven-pad and the regenerator pillar-walls 23, to the gas nozzles situated at the base of each flue. The volume of gas flowing to each distributor line 22, is regulated by means of the valve 41; and graduated orifice-plates, which may be changed from time to time, are provided in the accessible lower ends of the gas-ducts that extend up from the sub-structure passage-ways to the bases of the individual flame-flues.

Each regenerator has the usual sole-flue 24, and beneath each regenerator sole-flue 24, and extending approximately parallel therewith throughout its length, there is a ventilating duct 65 or subsole-channel 25 which is or structurally lies atop the oven-pad 11. Those four subsole-channels 25 lying beneath the sole-flues 24 of the four regenerator sections serving the heating-flues communicably connected with one series of cross-over flues, are inter-connected by means of lateral ducts 26 near their outer ends. At the inner end of each subsole-channel and adjacent to the regenerator division wall 27 extending the lengthwise axis of the battery, there is a port 28 which connects said channel with the basement

atmosphere substantially as shown. Ingress of air into the subsole-channels 25 is controlled by preferred adjustments on the valves 29. Thus, all combustion air which enters the regenerator sole-flues 24, enters the battery structure at ports 28, and in passing along the subsole-channels 25, absorbs heat from the oven-pad and the brickwork at the base of the sole-flues. Having traversed the length of the subsole-channel, this air then passes through valve 30, as shown by the arrows (Fig. 1) and enters the regenerator sole-flue 24, where it is distributed to the checker-brick above through the communicating openings 31.

Mechanical means are not necessary to effect the passage of air through the subsole-channel, the stack draft and chimney effect in the regenerators and heating-flues being sufficient for that purpose.

For effecting the reverse interval of gaseous flow in the regenerative heating cycle, when the former flame-flues become the waste heat flues and those regenerators which served for the inflow of air then carry the products of combustion to the stack, I have provided a novel mechanical device to accomplish the periodic flow reversal, as is shown in Figs. 3 and 4. I have also provided means for maintaining a flow of air in those subsole-channels 25 which at one period of the heating cycle lie beneath the sole-flues serving to flow combustion products from the regenerators into a waste heat tunnel 32, and which therefore do not discharge air into the regenerator sole-flues 24 above.

Referring to Figs. 3 and 4, the flow-box 33 is communicably connected by means of the pipe 34 with one of the waste-heat tunnels 32, and at one end bifurcates and by suitable sleeve connections 35 and packing is held in gas-tight connection with the regenerator sole-flues 24. Within each sleeve 35 is found a valve 30 which is operable by movement of the links 36 to open or close as preferred. Each valve 30 is provided with a valve-seat 37. Communication between the waste-heat tunnel 32 and the regenerator sole-flues 24 is established or broken by respectively opening or closing the valve 38 situated in the flow-box 33 at its junction with pipe 34. The valve 38 may be opened or closed by raising or lowering the counter-weight 39. The two valves 30 and valve 38 contained within one flow-box and serving two regenerator halves, are joined by the suitable lever links 36 and 40 so as to be actuated in unison by movement of the reversing cable 41 and in such manner as to close the valves 30 while opening 38 and vice versa. The damper valves 42 are manually operable to obtain preferred draft suction in either sole-flue.

As beforementioned, when air is no longer to be introduced through the valves 30 from the subsole-channels 25 into the sole-flues 24 and a new period of the heating cycle is to be initiated, the reversing cable is appropriately moved and the connecting chain moving over the pulley 43 raises the counter-weight 39, simultaneously effecting the closing of both valves 30 and opening of the valve 38, thereby establishing communication between the waste-heat tunnel 32 and the sole-flues 24.

By the same movement of the reversing cable, 70 similar valves in the adjacent flow-box associated with the other pair of sole-flues communicating, through the other regenerators and heating-wall, with the same series of cross-over flues near the top of the battery, are moved into the reverse 75

position, i. e., their valves 30 are opened and valve 38 is closed, thus permitting air to flow from the subsole-channels 25 into the regenerator sole-flues on the opposite side of the flow reversal plane.

From the aforesaid description of my invention it is apparent that the flow of air through the subsole-channels 25 is effected by the natural draft in the heating-flues and the combustion-products discharge-stack. With the closing of the valves 30 at the end of a period of the regenerative heating cycle and the consequent severing of communication between the sole-flues and their subsole-channels beneath, this agency to effect the movement of air in the subsole-channels is cut off. During one-half of the heating cycle, therefore, relatively little beneficial effect would be obtained from the presence of one-half of these ventilating means in the battery structure. To obviate this situation, and provide a flow of air in all subsole-channels during both periods of the heating cycle, I inter-connect near their outer ends by means of the ducts 26, the subsole-channels beneath those sole-flues which alternately supply air to or carry the products of combustion from those heating flues which are communicably connected as aforesaid by the same series of cross-over conduits 16. In this manner, all said subsole-channels are provided with a free flow path to the stack at all times; alternately, through the sole-flues directly above or by way of the ducts 26 and the adjacently associated subsole-channels.

In this embodiment of my invention, there is no direct communication between the air flow-boxes and the alley-ways 44. All air introduced into the battery for combustion purposes is drawn from the battery basement passages 45, which air as it is withdrawn, is replaced by air flowing from the alley-ways 44, over the flow-boxes and into the basement passages 45, as shown by the arrows in Fig. 1. A constantly changing flow of cool air through the alley-ways 44, the battery sub-structure passages 45 and the subsole-channels 25 is thereby maintained which serves to cool these parts of the battery structure and give proper operating conditions therein.

In my invention, the combustion air for the battery is constantly withdrawn from points substantially median of and distributed along the basement roof from one end to the other of the battery, and the air is drawn from directions that extend crosswise of the battery, from the open-topped alley-ways on the pusher-side and coke-side respectively toward the median line of intakes to the subsole-channels, so that not only is the warmest air in the sub-structure basement passages removed first but also the withdrawal is uniformly distributed over the whole area and is positive and controlled independently of outside atmospheric conditions.

A better appreciation will be obtained of the extent of the temperature control that is effected by thus maintaining a positive flow into and complete replacement of the air in the alley-ways and battery basement, when it is realized that a battery coking 1000 tons of coal per day will consume approximately 800 tons of air for the battery underfiring, and at such rate the air will be completely changed every four or five minutes in the basement space.

Not only does my invention provide a positive and effective means of cooling the basement structure of a battery of the aforementioned type, but as will be appreciated by reference to

Fig. 5, a substantial proportion of the zone between the oven-pad and the sub-structure comprises air spaces, which are good insulation media, serving as a barrier against heat transfer from the regenerators to the pad and basement structure beneath, the efficiency of which is augmented by the fact that the air is continuously changing therein and being replaced by air at a lower temperature.

To facilitate removal of dust or the like which may be deposited by the air passing through the ventilating channels and also make accessible for adjustments the valve 30, the removable plate 46 is provided. An air blast or any preferred means may be used to effect the dust removal.

The invention as hereinabove set forth is embodied in particular form and manner but may be variously embodied within the scope of the claims hereinafter made.

I claim:

1. A battery of horizontal coking retort ovens comprising, in combination, a series of alternate coking chambers and intermediate heating walls therefor arranged side-by-side, a series of cross-regenerators therefor beneath and paralleling the same with sole channels at the bottom of and communicating through ports with the regenerators, a structural pad supporting said regenerators and itself supported above a sub-structure providing accessible passageways throughout the basement of the battery, a system of under-jet firing for said heating walls comprising fuel gas connections leading from the basement directly to the heating flues and accessible from the basement and valved air-conduit connections leading from the basement to the sole flues of the regenerators for conveying the air for combustion from the basement to the sole flues of the regenerators for preheating for combustion, and a waste gas flue alongside the basement on at least one longitudinal side of the battery and having valved connections with the sole flues of the regenerators for off-flow of waste gas from the regenerators, openings being provided all along both the pusher-side and coke-side of the basement directly below the structural pad for indraft of the combustion air requirements of the battery into the basement from the outside atmosphere, the air inlets for substantially all of the air-conduit connections which lead from the basement to the sole flues of the regenerators being arranged and concentrated at substantially the region of the lengthwise middle of the top part of the basement so as to maintain throughout the basement, from the side openings at the cooler longitudinal coke- and pusher-sides of the battery all the way into the warmer lengthwise middle region of the basement, ventilating cross-drafts of the total volume of combustion air for the basement regenerator air inlets, with all air supplied to the regenerators from the basement by the regenerator sole flue air inlets therein confined to air substantially solely from sole flue air inlets at the warmer lengthwise middle region of the basement.

2. In a battery of horizontal coking retort ovens, in combination: a series of alternate coking-chambers and intermediate heating-walls therefor arranged side-by-side in a row, a series of cross-regenerators beneath and paralleling the same with sole channels at the bottom of and communicating through ports with the regenerators, a structural pad supporting said regenerators and sole channels and itself supported above a sub-structure providing accessible passage-ways

- throughout the basement of the battery, a system of under-jet firing for said heating-walls and accessible in said passage-ways, and series of subsole-channels intermediate the pad and the sole channels of the regenerator-chambers and paralleling the latter, said subsole-channels having ports for direct communication with the sole channels of the regenerators and having air-inlets arranged for intake of air along the middle of the basement roof at the longitudinal median line of said row, the communicating ports between the regenerators and their sole channels and the ports communicably connecting the sole and the sub-sole channels being so located relative to each other as to cause a flow of air through the sub-sole channels and thence through the sole channels from the air inlets to the sub-sole channels at the longitudinal median line of said row, and openings along the pusher-side and coke-side of the basement for in-draft of air from the outside atmosphere and maintaining through the basement cross-drafts from said side openings at the longitudinal sides of said row to said subsole-channel intakes along the middle of the basement roof at the longitudinal median line of said row.
3. A coke oven battery as in claim 2 and having waste-heat valve-means communicably connected with the sole channels for controlling outflow of waste heat from the sole channels, and having valve means for closing the ports of the subsole-channels between the sole channels and the sub-sole channels for disconnecting the latter from the sole-channels with which they directly communicate through such ports, when the aforesaid waste-heat valve-means are open during the waste-heat outflow periods of the reversal of the regenerators served by such sole-channels.
4. In a battery of horizontal coking retort ovens, in combination: a series of alternate coking-chambers and intermediate heating-walls therefor arranged side-by-side in a row, a series of cross-regenerators beneath and paralleling the same and having sole-channels individual to and under the respective regenerator-chambers, a structural pad supporting said regenerators and itself supported above a sub-structure providing accessible passage-ways throughout the basement of the battery, a system of under-jet firing for said heating-walls and accessible in said passage-ways, and series of sub-sole channels intermediate the pad and the sole-channels of the regenerators and paralleling the latter, said subsole-channels having ports for direct communication with the sole-channels of the regenerators and having air-inlets arranged for intake of air along the middle of the basement roof midway the longitudinal sides of said row, the communicating ports between the regenerators and their sole channels and the ports communicably connecting the sole and the sub-sole channels being so located relative to each other as to cause a flow of air through the sub-sole channels and thence through the sole channels from the air inlets to the sub-sole channels at the longitudinal median line of said row, and openings along the pusher-side and coke-side of the basement for in-draft of air from the outside atmosphere and maintaining through the basement cross-drafts from said side openings at the longitudinal sides of said row to said subsole-channel intakes along the middle of the basement roof midway the longitudinal sides of said row.
5. In a battery of horizontal coking retort ovens, in combination: a series of side-by-side coking chambers and intermediate heating-walls therefor arranged in a row, a series of cross-regenerators beneath and paralleling the same with sole-channels at the bottoms of and communicating through ports with the regenerators, a structural pad supporting said regenerators and sole-channels and itself supported above a sub-structure providing accessible passage-ways throughout the basement of the battery, a system of under-jet firing for said heating walls and accessible in said passage-ways, and series of sub-channels adjacent the structural pad and below the regenerator-chambers and paralleling the sole-channels of the latter, said sub-channels communicating through ports with the sole-channels of the regenerators and having air-inlets arranged for intake of air along the middle line of the basement roof midway of the longitudinal sides of said row, the communicating ports between the regenerators and their sole channels and the ports communicably connecting the sole and the sub-sole channels being so located relative to each other as to cause a flow of air through the sub-sole channels and thence through the sole channels from the air inlets to the sub-sole channels at the longitudinal median line of said row, and openings along the pusher-side and coke-side of the basement for in-draft of air from the outside atmosphere and maintaining through the basement cross-drafts from said side openings to said sub-channel intakes along the middle line of the basement roof midway of the longitudinal sides of said row.
6. A coke oven battery as in claim 5 and having waste-heat tunnels directly communicating with the sole-channels of the regenerators through valves for cutting off the sole channels from the waste-heat tunnels, and having separate valve-controlled connections at the outer ends of the sole channels for the ports between the sole-channels of the regenerators and sub-channels, and having the air supply means so adapted thereto as to have the whole air-requirement of the battery supplied to the regenerators from the sole channels through said sub-channels and the separate valve-controlled connections for the said ports.
7. In a coking oven retort battery of cross-regenerative coking ovens supported on a structural supporting pad and providing a basement beneath the pad, said battery being adapted for underfiring according to the under-jet principle, means for ventilating the basement by withdrawing from the basement at the longitudinal median of the battery the air required in the underfiring combustion reaction, comprising: subsole-channels beneath the sole-channels of the regenerators and extending substantially parallel to and adjacent the sole-channels in their lengthwise dimension, the subsole-channels having discharging ports near the longitudinal sides of the battery for communicable connection there with the regenerator sole-channels and having inlets communicating with the basement roof near the lengthwise axis of the battery, waste-heat valve-means for opening and closing communication of the sole channels with waste-heat withdrawal means therefor, and valve means for closing the ports between the sub-sole channels and the sole channels when the waste-heat valve-means therefor are open and for opening said ports when the waste-heat valve means are closed, that series of subsole-channels beneath regenerators which alternately supply air to or carry the products of combustion from the same series of oven heating flues being inter-connected near their discharge-

ing ports thereby providing regenerator communication to all such subsole-channels during both periods of the regenerative heating cycle.

8. Means for continuously changing the air in the alley-ways and basement structure of a coking oven retort battery of cross-regenerative coking ovens of the under-jet underfiring type supported on a structural pad with an accessible basement beneath, comprising: communicating open-ways 5 between the outer atmosphere and the alley-ways and basement, a series of sub-sole channels beneath the underfiring regenerator sole-channels and contiguous with the battery supporting pad and extending substantially parallel to the length- 10 wise axis of the sole-channels and adjacent thereto, said sub-sole channels having discharging ports near the sides of the battery and communicably connected with the regenerator sole-channels and having inlet ports communicating 15 with the basement at points near the longitudinal median line of the battery, means for controlling the flow of the basement air into said sub-sole channels at their inlet ports, valve-controlled-means for withdrawing combustion products 20 alternately from the sole channels on either side of the ovens' underfiring flow-reversal planes, valve-controlled-means for introducing the basement derived air from the sub-sole channels alternately 25 into the sole channels on either side of the ovens' flow-reversal planes, inter-connecting means between those sub-sole channels beneath regenerator sole-channels alternately supplying air to or carrying the combustion products from the same 30 series of oven heating flues, thereby providing 35 a continuous flow at all times of air through sub-

sole channels on both sides of the ovens' underfiring flow-reversal planes from the side open-ways into the alley-ways and across the battery basement and into the battery underfiring system at the longitudinal median line of the battery. 5

9. In a coking oven retort battery comprising a row of cross-regenerative coking chambers supported on a structural supporting pad elevated above accessible basement passage-ways, the chambers extending substantially parallel with 10 and alternately disposed between a series of vertically disposed heating flues, with regenerators beneath, the underfiring flow reversal planes being substantially parallel with the lengthwise axis of the coking chambers, beneath the regenerator 15 sole-channels and contiguous with the pad, a series of subsole-channels having discharging ports porting into the regenerator sole-channels near the longitudinal sides of said row and having inlet ports communicating with the basement air 20 near the longitudinal median line of said row and adapted to carry the air underfiring requirement of the battery, those subsole-channels which port into the regenerator sole-channels which alternately carry combustion air to or the products of 25 combustion from communicating heating flues being inter-connected for communication with each other near their discharging ports, means for alternately on each side of the flow reversal plane establishing communication between the 30 regenerator sole-channels and the waste-heat tunnel or the regenerator sole-channels and the underlying subsole-channel series.

JOSEPH BECKER. 35
